[57] CLAIM

The ornamental design for a bib, as shown and described.

DESCRIPTION

FIG. 1 is a front elevational view of a bib showing my new design;

FIG. 2 is a right side elevational view thereof, the side opposite being a mirror image;

FIG. 3 is a top plan view thereof;

FIG. 4 is a bottom plan view thereof;

FIG. 5 is a rear elevational view thereof; and

FIG. 6 is a front elevational view thereof, the bib being shown overlapped as if in use.

FIG. 1

FIG. 2

FIG. 3

FIG. 4

Fig. 6
